UNITED STATES PATENT OFFICE.

CURTIS A. SMITH, OF NEW ROCHELLE, NEW YORK, ASSIGNOR TO ROBERT FINDLAY MANUFACTURING CO., OF NEW YORK, N. Y., A CORPORATION OF NEW YORK.

DESIGN FOR A HANGING LAMP.

Application filed March 28, 1921. Serial No. 456,495. Term of patent 7 years.

To all whom it may concern:

Be it known that I, CURTIS A. SMITH, a citizen of the United States, residing at New Rochelle, in the county of Westchester and State of New York, have invented a new, original, and ornamental Design for Hanging Lamps, of which the following is a specification, reference being had to the ac-

companying drawing, forming part thereof.

Fig. 1 is a perspective view of a hanging lamp, embodying my new design.

Fig. 2 is a bottom view.

I claim:

The ornamental design for a hanging lamp, as shown.

CURTIS A. SMITH.
